TYPE-WRITING MACHINE.

1,268,790.

Specification of Letters Patent.

Patented June 4, 1918.

Application filed November 27, 1914. Serial No. 874,276.

To all whom it may concern:

Be it known that I, LEE S. BURRIDGE, a citizen of the United States, residing in the borough of Manhattan, city, county, and State of New York, have invented certain new and useful Improvements in Type-Writing Machines, of which the following is a specification.

This invention relates to type actions for writing machines, and one of the main objects of the invention is to produce a practicable writing machine of the class adapted for use of travelers, and for other uses in which compactness and light weight are desiderata. It has been proposed to have the upper portion of the machine fold down over the keyboard, for compactness for travelers' use; but according to the present invention, the machine, without the necessity of folding, is compact as said machine even in folded form; thus avoiding the necessity of using a folding mechanism, reducing expense, and increasing the durability and reliability of the machine.

To these ends I have devised a type action which permits the platen to be placed at a very low point in the machine. The type-bars are small, and hence normally occupy very little room; while on account of their small size they are comparatively strong and make clear imprints on the work-sheet, while being easy to operate by the keys. The type-bars lie normally in horizontal or cumbent positions, and may be placed over the key levers and very close thereto; the connections between the key levers and the type-bars being simple and not adding appreciably if any, to the height of the machine. These connections may be in the form of bell-crank having slot-and-pin engagement with the key levers, and having link connections to the type-bars, of a sort to decrease the leverage of the keys on the type-bars substantially during the printing strokes, thus rendering the touch of the keys very agreeable. The great difference in the width of the keyboard and in the width of the system of the small type-bars is compensated for by converging the links rearwardly to their points of attachment to the type-bars; the bell-crank being mounted in the same converging planes, to secure directness and ease of action, and avoid side strains or

binding effects upon the bell-crank; and the type-bar segment is inclined rearwardly from the vertical, so that each point of pivotal connection between type-bars and link shall move approximately in the same converging plane as the link itself. Moreover, the link and bell-crank are normally at an obtuse angle to each other, to give an easy start to the key; and this relationship is preserved for the entire converging system of bell-crank and links, so that the action of a key at the side of the keyboard is as satisfactory as at the middle of the keyboard. The whole device is very durable, compact, and easily operated; simple and inexpensive to manufacture, and not liable to get out of order.

In order to avoid too close convergence of the type-bar guiding-slots in the segment, these slots are cut radially to a center which is well beyond the printing center, so that successive slots in the segment are nearly parallel.

Although the type-bar arc is inclined rearwardly to about 30 degrees, the direction of shift of the platen at the case-shifting operation is made very nearly vertical, which is a desideratum.

Other objects and advantages will hereinafter appear.

Figure 1 is a sectional side elevation taken from front to rear of a typewriting machine embodying the present improvements.

Fig. 1^a is an elevation of a type-action at one side of the system.

Fig. 2 is a sectional front elevation to show the bell cranks and their mounts; some of the key levers being shown in cross section.

Fig. 3 shows a type-action in printing position.

Fig. 4 is a plan of the key levers and type-bars.

Fig. 5 is a diagram to illustrate the form and mounting of the type-bars; this view being taken about in the plane of the type-bar segment, which is inclined rearwardly from the vertical.

Each of the keys 1 is preferably used for printing a lower case letter, a capital letter, and a figure or character; the machine being preferably of the double case-shift class. These keys are mounted upon the forward

ends of levers 2 of the second order, which extend rearwardly beneath the type-bars 3 and close thereto, and are fulcrumed at their rear ends upon a transverse bar 4. Between 5 its ends, each key lever has a pin or wrist 5, to engage a slot 6 in an arm 7 of a bell crank. The other arm 8 thereof is pivoted at its upper end at 9 to the forward end of link 10, whose rear end is pivoted at 11 to 10 a short arm 12 which extends from the hub or rear portion of the type-bar 3. The bell cranks 7, 8, are fulcrumed upon studs 13, provided upon vertical plate-like brackets or mounts 14, secured upon the floor or base 15 15 of the typewriting machine.

The type-bars are arranged upon a segment 16, working in radial slots 17, and pivoted upon a curved fulcrum rod or wire 18. Each bar has a type-head 19, carrying three 20 types 20, to strike rearwardly against platen 21, which is shiftable to various points, as shown in dotted lines, to bring the printing line into register with the different types on the type-bars.

25 The construction is such as to afford an easy touch upon the keys and produce an exceedingly compact machine. One of the factors which contribute to the easy touch, is the very obtuse angle formed by the bell 30 crank arm 8 and the link 10 when in normal positions; whereby the leverage of the key upon the type-bar is rendered very great, and whereby such leverage decreases during the printing stroke and is least at the printing 35 position, Fig. 3, thus making the key very easy to start, and serving to cushion the weight of the operator's hand at the conclusion of the printing stroke. This result is also favored by the link 10, when in printing 40 position, Fig. 3, pulling in a line nearly radial to the type-bar pivot 18; the normal position of the pivot of the link to the short arm 12 of the type-bar favoring the easy start of the latter, and the positions of the 45 parts when the type is near the platen favoring a quick blow of the type and gradual arrest of the key.

It is also to be noted that ease of operation, clearness of type impressions and compactness of the machine are all aided by the 50 construction of the type-bar system itself. For securing room or clearance for the types when in normal positions, type-bars are usually made of comparatively great length; 55 but in the present instance, the type-bars are made short, and each is swung through a substantially greater arc than is the usual practice, from the printing position to normal position, in order to give the required 60 clearance. The shortness of the type-bar makes the touch on the key easy, and also enhances the clearness of the type impression on the sheet, and moreover conduces greatly to the compactness of the machine; 65 the types being directly back of the key-

board, and the types in the middle of the system being preferably lower than the back row of keys, the distance from the keys to the type-segment being very short, and the platen, owing to the shortness of the type-bars, being placed very low in the machine, so that the entire height of the machine may be little, if any, greater than the height of the base portion of the usual form of typewriting machine made for travelers' use. 70

To avoid the difficulty due to the low position of the platen in the machine, of reading the printing line thereon, I arrange the printing line above the platen axis, or in other words, on the upper front side of the platen, 80 where it is easily seen by the operator, even though considerably below the level of the operator's eye.

The type-bar segment is inclined rearwardly, preferably about 30 degrees from 85 the vertical, so that the rearwardly swinging types strike the platen after they have passed their highest points, so that the platen is set a little lower than if the usual plan were pursued of placing the platen vertically over the type-bar pivots; thus again reducing the height of the machine. The arrangement of the type-bar segment in a rearwardly inclined plane gives room for enough swing of the types away from the 90 printing point to enable them to clear one another normally, and to have many of the bars in the middle of the system lie about horizontally when in normal positions, so that said type-bars may be closed to the 95 underlying key levers, thus tending to produce compactness of the machine.

The keyboard is, of course, of standard width; but owing to the shortness of the type-bars, the width of the type-bar system 105 is very much less than customary, and far less than the width of the keyboard, or the system of key levers at their key ends. The problem of connecting up the members of the wide key-lever system to the members 110 of the very narrow type-bar system, especially in a manner to avoid undue side-pull and resultant binding upon the type-bars and connections, is solved, partly by converging the links from the bell-cranks to the 115 type-bars, and partly by the aforesaid rearward inclination of the type-bar segment, whereby each link extends in the general direction of the path taken by its rear pivot 11, so that undue sidewise stress upon the 120 type-bar is avoided. The bell-cranks preferably have the same converging arrangement as the links, so that the pivots 11 of the type-bars work approximately in the planes of their respective bell-cranks, thus 125 making very easy actions, and particularly favoring the effectiveness of the described normal obtuse arrangement of the links 10 and bell-crank arms 8 for the purpose specified; undue side stress being avoided on the 130

bell-cranks as well as on the links and type-bars, and the parts being compactly arranged, easily made and assembled, and not liable to get out of order.

- 5 The rear portion 2^a of the key levers are also preferably converged in planes parallel with the planes of their respective bell-cranks, the key levers being preferably mounted at their rear ends in a curve, Fig. 10 4, whose center is in rear of the key-lever system, so that the converging portions 2^a of the key levers shall be radial to the fulcrum bar 4, to avoid binding and simplify the manufacture. It will be understood that 15 the pairs 8, 10 work in converging planes with which the paths of their respective pivots 11 nearly coincide, so that the effectiveness of the pairs 8, 10 at the sides of the system is substantially the same as the middle 20 of the system, as illustrated at Fig. 1, notwithstanding the great discrepancy between the width of the type-bar system and the width of the keyboard; while the type-bars 3 are enabled to lie very near to the bottom 25 15 of the framework, and the position of the platen 21 is made correspondingly low, thus producing a practicable machine of very little height and otherwise of small dimensions.
- 30 The bell-crank arms 8 cross the key levers, the mounts 14 being below the key levers, and the links 10 above the key levers; and these links lie side-by-side with the type-bars, and hence do not add to the height of 35 the machine. The bell-cranks 7, 8 may be of substantially uniform size and shape, but mounted at different heights, those at the sides of the system being higher than those at the middle, and the pivots 13 forming a 40 curve which may be approximately concentric with the printing center 22 or the type-bar fulcrum wire 18, so that the relation of the parts 8 and 10 to the type-bars is substantially the same at the sides as at the middle of the system. The mounts 14 may be 45 made of gradually increasing heights from the middle to the sides of the system, to bring the arms 8 up to their proper positions in all cases. The pins 5 on the key levers 50 may be arranged at heights to correspond with the varying heights of the bell-cranks, and may be placed at varying distances from the fulcrum 4, so that the dip of the keys may be made uniform. The type-bars may 55 travel through about 120 degrees from their normal cumbent substantially horizontal positions to their printing positions.
- Two of the bell-cranks 7, 8 may be mounted upon each of the mounts 14, one bell- 60 crank upon each face, Fig. 2, each pair of bell-cranks extending up between adjacent key levers, and the spaces between the alternate key levers being occupied by the bell-cranks. This conduces to compactness of 65 manufacture and reliability in use, as well

as facility in removing and restoring parts of the machine for various purposes.

At Fig. 5 it will be seen that the slots 17 in the segment 16 radiate from a center 23 which is far above the printing center 22 70 which, at this figure, coincides with the center of the lower case or innermost type on the type-head 19; and that the bodies of the type-bars 3 are bent inwardly from their hub portions various extents, increasing as 75 the outer sides of the system are approached; and also that there are corresponding bends at the junctions of the bodies 3 of the type-heads 19, said bends occurring below the type-guide 25, which is preferably placed 80 just at the printing point. It is desirable to place the type-bars closely together, and this is favored by making the type-bars short, permitting the use of a short segment; but in order to avoid the consequent thinning 85 of the walls of the segment, due to cutting successive slots at considerable angles to each other, the slots are cut radial to the remote center 23, so that successive slots are more nearly parallel, so that the pivotal 90 points 11 on the rear ends of the type-bars shall not be too close together, thus affording room for the joints of the links 10 therewith. The type-bar fulcrum wire 18 may also be curved concentrically with the re- 95

Instead of arranging the printing point 100 on the platen in the usual manner, at the intersection of the platen surface with a radial line which is at right angles to the plane of the type-bar pivot arc, I arrange the printing point well below said intersecting point, Fig. 1, but higher than the axis of 105 the platen, so that the printing line is a little above the middle of the front side of the platen as illustrated, so that the platen shifts nearly in a vertical direction, which is a desideratum notwithstanding the fact that the arc of the type-bar segment is inclined well rearwardly for the purposes specified. The type-faces at Figs. 1 and 3 lie in a plane 110 which is tangent to the platen at a point a little higher than the horizontal axis of the platen, but below the aforesaid intersecting point.

It will be perceived that if the types were placed on the type-bars in the usual position, 120 they would be, when in printing position, inclined backwardly, substantially in parallelism with the inclined plane of the type-bar arc, and accordingly the platen would stand a little lower than shown in the drawings, 125 and the direction of the shifting movement would be parallel with said plane of the type-bar arc; but instead of their usual construction, the types are placed so that when in printing position they stand about ver- 130

tical, notwithstanding the rearward inclination of said type-bar pivot arc plane, and moreover the direction of the shift is about vertical. This substantially vertical arrangement gives advantages, the types striking a trifle above the horizontal plane of the axis of the platen, and the platen being given a substantially vertical movement, which can be effected by simple, inexpensive and compact mechanism, and the types standing nearly vertical when in printing position, so that the ribbon may stand accordingly, permitting the spools to have the usual vertical axes without the necessity of providing for the ribbon to make a troublesome backward cant at the printing point between the spools.

From the bottom end of each type-head extends a projection 26, which engages a spring finger 27, arranged near the platen, to be tensioned by each of the type-bars as it strikes the platen, and serving to start the type-bar promptly back toward normal position. The projection 26 may be integral with the bar itself as illustrated, being an extension of the type-head 19, which fits in the channeled types.

Each key lever may be provided with a return spring 28, in the form of a coil which is wholly mounted upon the lever itself, being caught at its forward end on a lug 29 projecting down from the key lever, and at its rear end in a hole 30 at the back of the key lever. This spring, at a point between its ends, bears upon a saddle-bar 31, which extends horizontally across the machine, to be used by all the springs 28. By this means, the key levers are supported in normal positions. The depression of each key tensions its spring over the bar 31, Fig. 3, and the recoil of the spring returns the key lever to normal position. This spring is inexpensive to make and assemble, and may be placed upon the lever before the latter is assembled at the machine, so that it is unnecessary, after assembling the levers, to catch the springs upon the usual hooks provided on the machine frame, thus saving expense. The key lever is detachably mounted on its fulcrum rod 4, and may be easily inserted or removed without regard to the spring, which finds its own place and needs no attention from the machinist. The lug or projection 29 may be made very thin, so that it may be bent forwardly or backwardly to vary the tension of the adjoining spring 28.

Variations may be resorted to within the scope of the invention, and portions of the improvements may be used without others.

Having thus described my invention, I claim:

1. A typewriting machine comprising a keyboard of standard size at the front of the machine, a system of normally cumbent rearwardly striking type-bars in rear of the keyboard and each carrying a group of types

of standard size, key-levers extending from the keyboard rearwardly and about horizontally beneath the type-bars and closely adjacent thereto, connections converging from the levers to the type-bars; said connections including converging sub-levers; the type-bars forming an arc-shaped group occupying about 90 degrees, the pivots of the type-bars arranged in an arc lying in a transverse plane inclined rearwardly about 30 degrees; the type-bars mounted to swing through about 120 degrees in their printing strokes, and the middle type-bars lying about level when at rest, with their types below the level of the highest keys, and the type-bars being so short that the types lie closely together when at rest; and a cylindrical platen to whose surface said plane is about tangential; said platen arranged in juxtaposition to the horizontal plane of the highest bank of keys in said keyboard and in rear of the type-bar pivots, with the printing line on the upper front side of the platen, to be struck by the type-bars as they swing rearwardly and downwardly from their highest positions.

2. A typewriting machine comprising a keyboard of standard size at the front of the machine, a system of normally cumbent rearwardly striking type-bars in rear of the keyboard and each carrying a group of types of standard size, key-levers extending from the keyboard rearwardly and about horizontally beneath the type-bars and closely adjacent thereto, connections converging from the levers to the type-bars; said connections including converging sub-levers; the type-bars forming an arc-shaped group occupying about 90 degrees, the pivots of the type-bars arranged in an arc lying in a transverse plane inclined rearwardly about 30 degrees; the type-bars mounted to swing through about 120 degrees in their printing strokes, and the middle type-bars lying about level when at rest, with their types below the level of the highest keys, and the type-bars being so short that the types lie closely together when at rest; and a cylindrical platen to whose surface said plane is about tangential; said platen arranged in juxtaposition to the horizontal plane of the highest bank of keys in said keyboard and in rear of the type-bar pivots, with the printing line on the upper front side of the platen, to be struck by the type-bars as they swing rearwardly and downwardly from their highest positions; said key-levers converging at their rear ends and working in converging planes, and said connections lying approximately in the working planes of said levers and approximately in the working planes of said type-bars respectively.

3. A typewriting machine comprising a keyboard of standard size at the front of the machine, a system of normally cumbent rear-

wardly striking type-bars in rear of the keyboard and each carrying a group of types of standard size, key-levers extending from the keyboard rearwardly and about horizontally beneath the type-bars and closely adjacent thereto, connections converging from the levers to the type-bars; the type-bars forming an arc-shaped group occupying about 90 degrees, the pivots of the type-bars arranged in an arc lying in a transverse plane inclined rearwardly about 30 degrees; the type-bars mounted to swing through about 120 degrees in their printing strokes, and the middle type-bars lying about level when at rest, with their types below the level of the highest keys, and the type-bars being so short that the types lie closely together when at rest; and a cylindrical platen to whose surface said plane is about tangential; said platen arranged in juxtaposition to the horizontal plane of the highest bank of keys in said keyboard and in rear of the type-bar pivots, with the printing line on the upper front side of the platen, to be struck by the type-bars as they swing rearwardly and downwardly from their highest positions; said connections lying approximately in the working planes of said key-levers and approximately in the working planes of said type-bars respectively, and including converging bell-cranks connected to said key-levers and working in the planes of said levers, and links converging rearwardly from said bell-cranks to said type-bars and extending nearly in the direction of the planes of movement of their respective bell-cranks and type bars, said bell-cranks and said links coöperating to afford a key-purchase which substantially diminishes during the printing stroke.

4. A typewriting machine comprising a keyboard of standard size at the front of the machine, a system of normally cumbent rearwardly striking type-bars in rear of the keyboard and each carrying a group of types of standard size, key-levers extending from the keyboard rearwardly and about horizontally beneath the type-bars and closely adjacent thereto, connections converging from the levers to the type-bars; the type-bars forming an arc-shaped group occupying about 90 degrees, the pivots of the type-bars arranged in an arc lying in a transverse plane inclined rearwardly about 30 degrees; the type-bars mounted to swing through about 120 degrees in their printing strokes, and the middle type-bars lying about level when at rest, with their types below the level of the highest keys, and the type-bars being so short that the types lie closely together when at rest; and a cylindrical platen to whose surface said plane is about tangential; said plate arranged in juxtaposition to the horizontal plane of the highest bank of keys in said key-board and in rear of the type-bar pivots, with the printing line on the upper front side of the platen, to be struck by the type-bars as they swing rearwardly and downwardly from their highest

positions; said connections lying approximately in the working planes of said key-levers and approximately in the working planes of said type-bars respectively, and including converging bell-cranks connected to said key-levers and working in the planes of said levers, and links converging rearwardly from said bell-cranks to said type-bars and extending nearly in the direction of the planes of movement of their respective bell-cranks and type bars, said bell-cranks and said links coöperating to afford a key-purchase which substantially diminishes during the printing stroke.

5. A typewriting machine comprising a keyboard at the front of the machine, a system of normally cumbent rearwardly striking pivoted type-bars directly in rear of the keyboard, levers of the second order converging from said keyboard rearwardly and fulcrumed at their rear ends; the type-bars lying very close to the key-levers, pull links extending forwardly from the rear ends of the type-bars, and bell-cranks to which the forward ends of said links are connected; said bell-cranks comprising upwardly-extending arms and forwardly-extending arms; said upwardly-extending arms connected at their upper ends to said links and extending down therefrom between the key-levers and fulcrumed at their lower portions, and said forwardly-extending arms directly engaging said levers to be depressed thereby, and said bell-cranks and links converging rearwardly to said type-bars, said upwardly-extending arms inclining rearwardly from their fulcrums, to be nearly in line with said links when in normal positions.

6. A typewriting machine comprising a keyboard at the front of the machine, a system of normally cumbent rearwardly striking pivoted type-bars directly in rear of the keyboard, levers of the second order converging from said keyboard rearwardly and fulcrumed at their rear ends; the type-bars lying very close to the key-levers, pull links extending forwardly from the rear ends of the type-bars, and bell-cranks to which the forward ends of said links are connected; said bell-cranks comprising upwardly-extending arms and forwardly-extending arms; said upwardly-extending arms connected at their upper ends to said links and extending down therefrom between the key-levers and fulcrumed at their lower portions, and said forwardly-extending arms directly engaging said levers to be depressed thereby, and said bell-cranks and links converging rearwardly to said type-bars, said upwardly-extending arms inclining rearwardly from their fulcrums, to be nearly in line with said links when in normal positions, and said links being about radial to the type bar pivots when the type-bars are in printing positions.

7. The combination of a system of rearwardly striking type-bars pivoted at their rear ends and normally cumbent; said type-bars pivoted in an arc; a system of key-
5 operated bell-cranks mounted below the type-bars; and pull links extending rearwardly from said bell-cranks to said type-bars and pivoted to the latter; said system of bell-cranks being substantially wider than
10 said system of type-bars and working in rearwardly converging planes, said links extending substantially in said converging planes, and said arc being in a transverse plane that is inclined rearwardly about 30
15 degrees, to cause the general direction of movement of the rear end of each link to be approximately in the direction of the length of the link.

8. The combination of a system of rearwardly striking type-bars pivoted at their rear ends and normally cumbent; said type-bars pivoted in an arc; a system of key-
20 operated bell-cranks mounted below the type-bars; and pull links extending rearwardly from said bell-cranks to said type-bars and pivoted to the latter; said system of bell-cranks being substantially wider than said system of type-bars and working in rearwardly converging planes, said links ex-
25 tending substantially in said converging planes, and said arc being in a transverse plane that is inclined rearwardly about 30 degrees, to cause the general direction of movement of the rear end of each link to be approximately in the direction of the length of the link, and said link normally forming an obtuse angle with the arm of
30 the bell-crank to which it is connected, to co-operate with said arm to diminish the leverage of the key at the printing stroke.

9. The combination of a system of rearwardly striking, normally cumbent type-bars pivoted at their rear ends in an arc which is in a transverse plane that inclines rearwardly at an angle of about 30 degrees; a system of bell-cranks mounted below the type-bars; pull links extending rearwardly from said bell-cranks to the type-bars and pivoted to the latter; and a system of levers bearing keys at their forward ends and extending rearwardly beneath the type-bars and connected to said bell-cranks; the system of key-levers and the system of bell-cranks being both substantially wider than
45 the system of type-bars, and said key-levers converging at their rear portions; the bell-cranks working in vertical planes which converge in accordance with the convergence of the key-levers, and the links extending
50 in substantially said vertical planes; and the movements of the pivots of the links to the type-bars being nearly within said vertical converging planes, respectively.

10. The combination of a system of rearwardly striking, normally cumbent type-

bars pivoted at their rear ends in an arc which is in a transverse plane that inclines rearwardly at an angle of about 30 degrees; a system of bell-cranks mounted below the type-bars; pull links extending rearwardly from said bell-cranks to the type-bars and pivoted to the latter; and a system of levers bearing keys at their forward ends and extending rearwardly beneath the type-bars and connected to said bell-cranks; the system of key-levers and the system of bell-cranks being both substantially wider than the system of type-bars, and said key-levers converging at their rear portions; the bell-cranks working in vertical planes which converge in accordance with the convergence of the key-levers, and the links extending substantially in substantially said vertical planes; and the movements of the pivots of the links to the type-bars being nearly within said vertical converging planes, respectively, said bell-cranks having arms to which the forward ends of said links are pivoted; said arms extending upwardly and rearwardly to the links and forming obtuse angles therewith.

11. The combination of a system of rearwardly striking type-bars, pivoted at their rear ends and normally cumbent; said type-bars pivoted in an arc; a system of key-operated bell-cranks mounted below the type-bars; and pull links extending rearwardly from said bell-cranks to said type-bars and pivoted to the latter; said system of bell-cranks being substantially wider than said system of type-bars and working in rearwardly converging planes, said links extending substantially in said converging planes, and said arc being in a transverse plane that is inclined rearwardly about 30 degrees, to cause the general direction of movement of the rear end of each link to be approximately in the direction of the length of the link, and said link normally forming an obtuse angle with the arm of the bell-crank to which it is connected, to coöperate with said arm to diminish the leverage of the key at the printing stroke, said bell-crank arms being of substantially uniform size, and the bell-cranks being pivoted in an arc about concentric with the type-bar pivot arc, so that the movements of the bell-cranks and links are substantially uniform for all the type-bars.

12. The combination of a system of rearwardly striking, normally cumbent type-bars pivoted at their rear ends in an arc which is in a transverse plane that inclines rearwardly at an angle of about 30 degrees; a system of bell-cranks mounted below the type-bars; pull links extending rearwardly from said bell-cranks to the type-bars and pivoted to the latter; and a system of levers bearing keys at their forward ends and extending rearwardly beneath the type-bars and connected to said bell-cranks; the system

of key-levers and the system of bell-cranks being both substantially wider than the system of type-bars, and said key-levers converging at their rear portions; the bell-cranks working in vertical planes which converge in accordance with the convergence of the key-levers, and the links extending in substantially said vertical planes; and the movements of the pivots of the links to the

type-bars being nearly within said vertical converging planes respectively, said bell-cranks having arms to which the forward ends of said links are pivoted; said arms extending upwardly and rearwardly to the links and forming obtuse angles therewith, said bell-crank arms being of substantially uniform size, and the bell-cranks being pivoted in an arc about concentric with the type-bar pivot arc, so that the movements of the bell-cranks and links are substantially uniform for all the type-bars.

13. The combination of a system of rearwardly striking type-bars, key-levers extending beneath the type-bars, sub-levers between the key-levers and type-bars, and mounts whereon the sub-levers are pivoted; said sub-levers arranged in pairs, one pair on each of said mounts, the members of the pair being on opposite faces of the mount.

14. The combination of a system of rearwardly striking type-bars, key-levers extending beneath the type-bars, sub-levers between the key-levers and type-bars, and mounts whereon the sub-levers are pivoted; said sub-levers arranged in pairs, one pair on each of said mounts, the members of the pair being on opposite faces of the mount, said pairs occupying alternate spaces between the key levers.

15. The combination of a system of rearwardly striking type-bars pivoted in an arc, key-levers extending rearwardly beneath the type-bars, a system of bell-cranks, pull links extending from arms of said bell-cranks to said type-bars, said arms normally at obtuse angles to said links, to coöperate therewith in decreasing the leverage of the keys during the printing strokes, said bell-cranks of approximately uniform size, and mounted in a curve approximately concentric with the curve of the type-bar pivots, and said key-levers having pin-and-slot connections to said bell-cranks at various heights on the key-levers to correspond with the positions of the bell-cranks.

16. The combination with a system of key-levers, of a bar extending transversely of the system, and helical returning springs upon said levers, each spring connected at both ends to its lever and bearing between its ends against said bar, to be tensioned thereby upon the depression of the key.

17. The combination with a system of key-levers, of a bar extending transversely of the system, and helical returning springs

upon said levers, each spring connected at both ends to its lever and bearing between its ends against said bar, to be tensioned thereby upon the depression of the key, each lever having a lug upon which one end 70 of the spring is caught, to afford clearance for the spring when bending upon said bar, and said lug being bendable to adjust the tension of the spring.

18. A system of pivoted type-bars mounted with their pivots arranged in an arc, each type-bar having a type-head carrying a plurality of types, the bodies of the bars forming various angles with the type-heads at the inner ends of the latter, said arc 80 struck from a point far above or beyond the printing center, the type-bars swinging in planes radial to said point, and the bodies of the type-bars being variously bent inwardly from the hub portions thereof. 85

19. A system of pivoted type-bars mounted with their pivots arranged in an arc, each type-bar having a type-head carrying a plurality of types, the bodies of the bars forming various angles with the type-heads 90 at the inner ends of the latter, said arc struck from a point far above or beyond the printing center, the type-bars swinging in planes radial to said point, and the bodies of the type-bars being variously bent inwardly from the hub portions thereof, said type-bars working in slots in a segment, said slots radial to said point, and a fulcrum-wire concentric with said point on which the type-bars are pivoted. 100

20. The combination of a system of rearwardly striking normally cumbent type-bars pivoted at their rear ends in an arc which is in a transverse plane that inclines rearwardly at an angle of about 30 degrees; 105 a system of bell-cranks mounted below the type-bars; pull links extending rearwardly from said bell-cranks to the type-bars and pivoted to the latter; and a system of levers bearing keys at their forward ends and extending rearwardly beneath the type-bars and connected to said bell-cranks; the system of key-levers and the system of bell-cranks being both substantially wider than the system of type-bars, and said key-levers 110 converging at their rear portions; the bell-cranks working in vertical planes which converge in accordance with the convergence of the key-levers, and the links extending in substantially said vertical planes; 120 and the movements of the pivots of the links to the type-bars being nearly within said vertical converging planes, respectively, each type-bar having a type-head carrying a plurality of types, the bodies of the bars 125 forming various angles with the type-heads at the inner ends of the latter, said arc struck from a point far above or beyond the printing center, the type-bars swinging in planes radial to said point, and the bodies 130

of the type-bars being variously bent inwardly from the hub portions thereof.

21. The combination of a system of rearwardly striking type-bars pivoted at their rear ends and normally cumbent; said type-bars pivoted in an arc; a system of key-operated bell-crank mounted below the type-bars; and pull links extending rearwardly from said bell-crank to said type-bars and pivoted to the latter; said system of bell-crank being substantially wider than said system of type-bars and working in rearwardly converging planes, said links extending substantially in said converging planes, and said arc being in a transverse plane that is inclined rearwardly about 30 degrees, to cause the general direction of movement of the rear end of each link to be approximately in the direction of the length of the link, and said link normally forming an obtuse angle with the arm of the bell-crank to which it is connected, to co-operate with said arm to diminish the leverage of the key at the printing stroke, each type-bar having a type-head carrying a plurality of types, the bodies of the bars forming various angles with the type-heads at the inner ends of the latter, said arc struck from a point far above or beyond the printing center, the type-bars swinging in planes radial to said point, and the bodies of the type-bars being variously bent inwardly from the hub portions thereof.

22. In a typewriting machine, comprising a keyboard at the front of the machine, a system of normally converging rearwardly striking type-bars directly in rear of the keyboard and each carrying a group of types, there being one type-bar for each type key on the keyboard, depressible key-levers extending from the keyboard rearwardly and about horizontally beneath the type-bars and juxtaposed thereto, the system of type-bars forming an arc-shaped group, the pivots of the type-bars arranged in an arc lying in a transverse plane inclined rearwardly about 30 degrees, the type-bars mounted to swing through about 120 degrees in their printing strokes, and the middle type-bars lying about level when at rest, with their types nearly level with the highest keys, the type-bars lying compactly together in normal positions, and being so short that they fill a segment or arc of about 90 degrees, so that the outer type-bars swing in planes inclined at about 45 degrees to the horizontal, the width of the system of types being materially less than the width of the keyboard, and converging connections extending from the type-bars to the key-levers, and including a system of sub-levers which converge rearwardly toward the type-bars.

23. In a typewriting machine, comprising a keyboard at the front of the machine, a system of normally converging rearwardly

striking type-bars directly in rear of the keyboard and each carrying a group of types, there being one type-bar for each type key on the keyboard, depressible key-levers extending from the keyboard rearwardly and about horizontally beneath the type-bars and juxtaposed thereto, the system of type-bars forming an arc-shaped group, the pivots of the type-bars arranged in an arc lying in a transverse plane inclined rearwardly about 30 degrees, the type-bars mounted to swing through about 120 degrees in their printing strokes, and the middle type-bars lying about level when at rest, with their types nearly level with the highest keys, the type-bars lying compactly together in normal positions, and being so short that they fill a segment or arc of about 90 degrees, so that the outer type-bars swing in planes inclined at about 45 degrees to the horizontal, the width of the system of types being materially less than the width of the keyboard, and converging connections extending from the type-bars to the key-levers, and including a system of sub-levers which converge rearwardly toward the type-bars, and are connected by converging links to the type-bars, each link moving approximately in the plane in which its type-bar swings and being inclined upwardly from its front to its rear end.

24. A typewriting machine comprising a keyboard at the front of the machine, a system of normally cumbent rearwardly striking type-bars directly in rear of the keyboard, said type-bars with their types lying about on a level with the keys, levers having fulcrums and converging from said keyboard rearwardly and working in substantively converging planes, and connecting trains extending from the rear ends of said type-bars forwardly and downwardly to points below the key-levers, said trains comprising bell-crank forward of the type-bars and connected to said levers, and having bearings on the framework below the level of the key-lever fulcrums, said bell-crank converging rearwardly toward the type-bars and swinging in the planes of said levers respectively, and also comprising links converging rearwardly from said bell-crank beneath the type-bar pivots and attached to arms extending rearwardly from said type-bars, and lying nearly in the planes of movement of their respective type-bars.

25. A typewriting machine comprising a keyboard at the front of the machine, a system of normally cumbent rearwardly striking type-bars directly in rear of the keyboard and of substantively less width than the keyboard, levers converging from said keyboard rearwardly and working in substantively converging planes, bell-crank forward of the type-bars and connected to said levers and converging rearwardly toward

- their respective type-bars and swinging in the planes of said levers respectively, and links extending from said bell-cranks and substantively converging rearwardly to said 5 type-bars and lying nearly in the planes of movement of their respective type-bars, said bell-cranks comprising arms to which said links are connected, each of said arms normally making an obtuse angle to its link to 10 afford a substantively decreasing leverage of the key on its type-bar during the printing stroke.
26. A typewriting machine comprising a keyboard at the front of the machine, a system of normally cumbent rearwardly striking type-bars directly in rear of the keyboard and of substantively less width than the keyboard, levers converging from said keyboard rearwardly and working in substantively converging planes, bell-cranks 20 forward of the type-bars and connected to said levers and converging rearwardly toward their respective type-bars and swinging in the planes of said levers respectively, and links extending from said bell-cranks and substantively converging rearwardly to said type-bars and lying nearly in the planes of movement of their respective type-bars, said bell-cranks comprising arms to which 25 said links are connected, each of said arms normally making an obtuse angle to its link to afford a substantively decreasing leverage of the key on its type-bar during the printing stroke, and said link extending nearly 30 radially to the type-bar pivot when the type is in printing position.
27. A typewriting machine comprising a keyboard at the front of the machine, a substantively narrower system of normally cumbent rearwardly striking pivoted type-bars 35 directly in rear of the keyboard, levers of the second order converging substantively from said keyboard rearwardly and fulcrumed at their rear ends; the type-bars
- lying very close to the key-levers, pull links 45 extending forwardly from the rear ends of the type-bars, and bell-cranks to which the forward ends of said links are connected; said bell-cranks comprising upwardly-extending arms and forwardly-extending 50 arms; said upwardly-extending arms connected at their upper ends to said links and extending down therefrom between the key-levers and fulcrumed at their lower portions, and said forwardly-extending arms directly 55 engaging said levers to be depressed thereby, and both said bell-cranks and said links substantively converging rearwardly to said type-bars.
28. In a case-shift typewriting machine, 60 the combination with a revoluble platen, of a system of key-levers, a system of short type-bars each carrying at least three types and pivoted in an arc below the platen and above the key-levers, each type-bar swinging 65 through substantively more than ninety degrees, the type-bars at the center of the system lying normally in about horizontal positions, the arc of the type-bar pivots lying in a plane inclined rearwardly, the printing 70 line on the platen being higher than the platen axis, but well beneath a radial line drawn from the platen center at right angles to said type-bar pivot-arc plane, and the line of the type faces when in printing 75 position being about vertical and tangent to the platen at said printing line, the different types on the bars being designed to be brought into use by a relative shift between the bars and the platen in a direction which 80 is approximately vertical, to permit the arrangement of the ink ribbon about vertically on edge.
